FIG. 1

FIG. 2

FIG. 3

FIG. 4

FIG. 5

FIG. 6

FIG. 7

FIGURE 1 is a plan view of a deck of game cards showing a group of eight cards in which the upper suits are spades;

FIGURE 2 shows a group of three cards having upper suits in spades, a card having an upper suit in hearts, and a group of four cards having upper suits in clubs;

The backs of the cards are conventional.

The characteristic features of my design reside particularly in the combination of the playing cards and their grouping, the narrow shape of the face cards and their relationship to the remaining indicia as shown.

I claim:

The ornamental design for a deck of game cards, as shown and described.
